CLAIM

The ornamental design for a baby swaddle, as shown and described.

DESCRIPTION

FIG. 1 is a front view of a baby swaddle showing my new design;

FIG. 2 is a back view of the baby swaddle shown in FIG. 1; FIG. 3 is a front view of the baby swaddle shown in FIG. 1 with the bottom wing in a folded configuration;

FIG. 4 is a front view of the baby swaddle of FIG. 1 with the bottom wing and the left wing in a folded configuration; and, FIG. 5 is a front view of the baby swaddle of FIG. 1 with the bottom wing, the left wing and the right wing in a folded configuration.

The thickness of the baby swaddle is nominal as compared to the length and width as evidenced in FIGS. 3-5, therefore top, bottom and side views of the baby swaddle are not shown. The broken lines showing the stitching are for illustrative purposes only and form no part of the claimed design.
